CLAIM

We claim, the ornamental design for a finger ring type portable information terminal, as shown and described.

DESCRIPTION

FIG. 1 is a front view of a finger ring type portable information terminal showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front perspective view thereof; and,

FIG. 8 is a reference view of the finger ring type portable information terminal displaying an example of information. In the drawings, the broken lines depict environmental subject matter only that forms no part of the claim.

The finger ring type portable information terminal can function as a computer, a media reproducing device (e.g., a music player, a video player, or a game player), a media storage device, a communication device (e.g., a portable telephone), a medical device (e.g., a device including a pulse sensor, a blood pressure sensor, or a body temperature sensor) or the like, for example. The finger ring type portable information terminal is wearable on a finger or the like and used as an accessory.
